UNITED STATES PATENT OFFICE.

DOLLETTA MAY ACKERMAN, OF LONG BEACH, CALIFORNIA.

HAIR CURLER.

Application filed June 27, 1925. Serial No. 40,020.

To all whom it may concern:

Be it known that I, DOLLETTA MAY ACKERMAN, a citizen of the United States, residing at Long Beach, in the county of Los Angeles and State of California, have invented a new and useful Hair Curler, of which the following is a specification.

This invention relates to toilet articles and more particularly to hair curlers or crimpers.

10 The object of the invention is to provide a simple and efficient device of this character whereby the hair may be curled without the use of heat and which is so constructed that the end of the lock to be curled will be securely held before the lock is wound on the curler.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within 20 the scope of what is claimed without departing from the spirit of the invention.

In the accompanying drawings:—

Figure 1 represents a plan view of a curler constructed in accordance with this invention with a lock of hair shown clamped thereby and with parts broken out to show the fabric covering.

Figure 2 is an edge view thereof; and

Figure 3 is a side elevation of the curler shown in operative position with the hair wound thereon.

In the embodiment illustrated the curler 1 constituting this invention which is especially adapted for curling comparatively short or bobbed hair, comprises a pliable metal strip which when folded will retain its position. One end of this flat strip is made wider than the other as shown at 2 and has a shoulder 3 at its inner end to prevent the clamp securing band 5 from sliding off the curler and being lost.

This metal strip is covered with any suitable fabric 4 to protect the hair against cutting by the metal.

A flat flexible steel clamp is shown in the form of a tapered finger 6 which is attached to the body of the curler by means of an eyelet rivet 7 passing through the body of the curler.

The steel slide 5 in the form of a band extends around the strip 1 and is slidable thereon to engage the free end of the clamp 6 to hold the clamp in operative position.

In the use of this curler the band 5 is slipped forward to release the clamp 6 and one end of the lock to be curled is placed between the clamp and the body of the curler as shown in Figure 1 and the clamp swung into position and secured by the sliding band 5. The lock is then wound on the curler tightly to the desired extent and then the pliable metal ends of the body of the curler are folded over into the position shown in Figure 3, which securely holds the curl on the iron and retains it until manually released.

From the above description it will be obvious that the sliding metal band 5 will securely hold the ends of clamping finger 6 so that the lock when wound thereon will not accidentally release and by making the curler of flat pliable metal it will be comfortable to be worn at night while sleeping.

By making the curler of flat metal and constructing it as shown provides for the slipping of the curl from the curler without necessitating unwinding thereof.

I claim:—

A hair curler comprising a flat metal strip having a longitudinally extending clamping finger secured at one end to one face thereof and provided with means for detachably securing the free end of said finger, one edge of said metal strip being wider than the remainder thereof, and a metal band slidable on said curler to secure the free end of the clamping finger.

In testimony that I claim the foregoing as my own, I have hereto affixed my signature.

DOLLETTA MAY ACKERMAN.
